(57) **CLAIM**

The ornamental design for a security stick, as shown and described.

DESCRIPTION

FIG. 1 is a front left view of a security stick in a closed assembled configuration, showing my new design;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a front left view of a security stick in an open assembled configuration;
FIG. 9 is a front left view of a security stick in a disassembled configuration;
FIG. 10 is a front elevation view thereof;
FIG. 11 is a rear elevation view thereof;
FIG. 12 is a left elevation view thereof;
FIG. 13 is a right elevation view thereof;
FIG. 14 is a top plan view thereof; and,
FIG. 15 is a bottom plan view thereof.
The broken lines represent threaded regions of a security stick which form no part of the claimed design.
